UNITED STATES PATENT OFFICE.

ANTONIO DI SALVIO, OF WASHINGTON, PENNSYLVANIA.

HAIR-CLEANING DEVICE.

1,308,685.

Specification of Letters Patent.

Patented July 1, 1919.

Application filed February 15, 1919. Serial No. 277,199.

To all whom it may concern:

Be it known that I, ANTONIO DI SALVIO, a citizen of the United States, residing at Washington, in the county of Washington and State of Pennsylvania, have invented certain new and useful Improvements in Hair-Cleaning Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in hair cleaning appliance and consists of a simple and efficient device of this character having various details of construction combination and arrangement of parts, which will be hereinafter fully described, shown in the accompanying drawings and then specifically defined in the appended claim.

I illustrate my invention in the accompanying drawings which, with the letters of reference marked thereon, form a part of this application, and in which:

Figure 1 is a vertical sectional view, parts being shown in elevation, and

Fig. 2 is an enlarged detail view in vertical section showing the valve passageway and connections therewith.

Reference now being had to the details of the drawings by letter:

A designates a casing adapted to contain a motor B having a fan C fixed to the shaft C' thereof, said fan being adapted to rotate in a horizontal plane within a suitable housing. Leading from the latter is a pipe D having a nipple D' to which the flexible pipe E is connected, and which latter is connected to a hollow handle F having a comb F' at one end. Said comb is provided with perforations H and through which air may be drawn, and I designate teeth of the comb. On of the branching passageways of the fan

has nipple connection with a pipe O, which in turn is connected to a hollow handle N with a head N' having perforations therein and which is adapted to be used for drying the hair, by permitting a blast of air to be blown through said perforations N'. A double valve Q is mounted in the branching pipe O and may be shut off when desired, and R designates a receptacle at the end of a branching passageway T leading from the fan casing. Said valve Q extends through the pipe T and is provided with two oppositely disposed passageways Q' and Q², in order that the pipe T may be shut off when the pipe O is open and vice versa.

Electrical wires W connect with the motor and afford means for supplying current to drive the latter.

In operation, when it is desired to utilize the comb, the fan is set in motion and when the comb is in use the air may be drawn through passageways, drawing the dandruff and which may be deposited in the receptacle R at the end of the branching passageway T, the valve Q being closed. When the drier is used the valve Q may be opened and the valve in the passageway T closed.

What I claim to be new is:

A hair cleaning apparatus, comprising a casing, a motor, a vertically disposed shaft with a fan fixed thereto, and a suitable housing for the latter, a pipe leading from the housing, a handle with flexible pipe connections between the fan and the housing, a comb with perforations fastened to said handle, said housing having branching passageways with valves therein, a drier having flexible pipe connection with one of said passageways and a receptacle with the other adapted to receive dandruff.

In testimony whereof I hereunto affix my signature in presence of two witnesses.

ANTONIO DI SALVIO.

Witnesses:

WILLIAM T. POWER,
STEVE CORDA.
